HEAT AND PRESSURE APPLYING APPARATUS

Joseph Marziani, Philadelphia, Pa.

Application November 5, 1946, Serial No. 709,081

4 Claims. (Cl. 154—42)

1

My invention relates to a heat and pressure applying apparatus of the type adapted to be used for sealing the mouths of bags or for laminating other sheets made of fusible material by applying heat and pressure thereto. One form of such apparatus is disclosed in my prior Patent No. 2,414,157 entitled "Heat and pressure applying device."

One object of the invention is to produce an improved apparatus of the type set forth.

A further object is to produce an improved apparatus of this type which is provided with means for automatically folding the mouth of the bag upon itself prior to the application of heat and pressure thereto.

A still further object is to produce an improved apparatus of this type in which the folding action is conveniently and accurately controlled.

A still further object is to produce an improved apparatus in which the folding operation is performed in the course of the application of heat and pressure to the members to be joined.

These and other objects are attained by my invention as set forth in the following specification and as illustrated in the accompanying drawings in which:

Fig. 1 is a top plan view of the improved apparatus embodying my invention.

Fig. 1a is a fragmentary top plan view showing details of construction.

Fig. 2 is a view, partly in elevation and partly in vertical section, of the apparatus shown in Fig. 1, certain parts being broken away.

Fig. 3 is a front elevational view, certain parts being broken away to show details of construction.

Fig. 4 is a vertical sectional view, looking in the direction of line 4—4 on Fig. 1.

Fig. 5 is a diagrammatic view, showing the apparatus as it appears during the folding operation and prior to the application of pressure on the mouth of the bag.

Fig. 6 is a diagrammatic view, showing the apparatus after completion of the folding operation and as it appears during the first stage in the application of heat and pressure.

Fig. 7 is a view similar to Fig. 6, showing the apparatus as it appears during the final stage in the application of heat and pressure, and just prior to its return to the non-operating position of Fig. 5.

Figs. 8, 9, 10 and 11 are fragmentary views showing details of construction.

Referring to the drawings, 12 designates a base casting adapted to be secured by bolts 14 passing 55

2

through holes 15 to a support or platform 16. At the front thereof, the casting 12 carries a fixed lower jaw 18 provided with an opening 19 for receiving a tubular heating element 20 (Fig. 3). 5 The heating element is preferably of the well-known type.

Coacting with the lower fixed jaw 18 is an upper articulated jaw 24 which is also provided with an opening similar to the opening 19 for receiving another tubular heating element 20. 10 The heat of the jaws 18 and 24 may be measured and regulated by any suitable conventional means 25. The upper jaw 24 is suspended from a head 26 by means of slide bolts 27 (Figs. 1 and 3) and 15 is cushioned by springs 28 seated in recesses formed in the under side of the head 26. The tension of the springs 28 may be regulated by means of screws 29 or the like. The head 26 is carried by the front ends of forwardly diverging arms 30 carried by or formed at the end of an arm 32. The spaced arms 30 are connected by a cross piece 34 in which is mounted a vertically adjustable threaded bolt or stem 36, which will hereinafter be further referred to.

20 The arm 32 is connected by a pivot pin 40 to a pair of links 42 which, in turn, are secured, by a pivot pin 44, to a lug 46 formed on a rocker arm 48. The rocker arm 48 is provided, at one end thereof, with a transversely disposed sleeve 50 25 through which extends a pivot pin 52, which engages vertical walls 54 of the base casting 12. The rocker arm 48 is thus rotatable about the axis of the pin 52.

Near its other end, the rocker arm 48 is connected, by means of a pivot pin 60, to a pair of links 62 which are, in turn, connected, by means of a pivot pin 64, to the end 65 of an operating lever 66. The operating lever 66 is fulcrumed on a pivot pin 68 which is secured to pendant portions 70 of the base casting 12. The operating lever 66 terminates in a foot-operated pedal (not shown), or, if desired, a prime mover acting on the pivot pin 64 may be employed for actuating the apparatus.

40 At the end of the rocker arm 48 is fixed a pendant latch 76, the lower hooked end of which is adapted to engage a sliding bolt 78, which is urged toward the latch by a spring 80. The operating lever is also provided with a recess in 45 which is positioned a spring 82, which forms a cushioned stop for the downward movement of the adjacent end of the rocker arm 48 when the latter moves to the non-operating position of Fig. 2. The spring 82 also yieldably abuts the under side of the adjustment bolt 36 when the ap-

paratus assumes the final stage of its operation, as shown in Fig. 7. This action will be further referred to.

On vertical side lugs 84, disposed near the ends of the arms 30, are mounted angle brackets 86 which carry bearings 87, which are disposed above the jaws and in which is journalled a rod 88. To the rod 88 are fixedly secured spaced arms 90 carrying a blade 91. The blade 91, in one position of the apparatus, is adapted to enter between the upper and lower jaws to fold the mouth of a bag or other material in a manner and for a purpose hereinafter set forth.

To the rod 88 is also fixedly secured one end of an arm 92, the other end of which is connected, by means of a pivot pin 93, to the upper end of a link 94. The lower end of the link 94 is pivoted, at 95, to an arm 96, one end of which is rotatable on a pin 97 secured to the side lugs 84, and the other end of which terminates in a sleeve 102. The sleeve 102 houses the bolt 78 and the spring 80 above mentioned, and also carries an adjustment device, best shown in Figs. 8 to 11, for regulating the position of the bolt 78. This adjustment device includes a vertical plate 106 pivoted at 107 to the arm 96 and provided with an arcuate slot 108 through which projects a pin 110 which is carried by the bolt 78. The pin 110, under action of the spring 80 on the bolt 78, is moved to the left and engages the left-hand wall of the slot 108 as viewed in the drawings, thus limiting the extent to which the bolt 78 may project outwardly of the sleeve 102. The plate 106 is secured to a plate 112 by means of a bolt 113 engaging a vertical slot in the plate 112, so that the plate 106 may be raised or lowered relative to the plate 112, thereby changing the position of the pin 110 and, hence, the bolt 78 relative to the slot 108. The arm 112 is movable with the arm 96 and may be secured or may form part of the arm 96 or the sleeve 102.

The arms 92, 94 and 96 are biased downwardly by a spring 118 anchored at its upper end to the pivot pin 93 and secured at its lower end to a fixed point 119 carried by the base casting 12. The downward movement of the arm 96 and the parts carried thereby is limited, by means of a stop 120, which is carried by or forms part of the base casting and which is preferably resilient so as to cushion the shock and deaden the noise.

Operation

In using the apparatus described, the operator slips the mouth 122 of a bag, or other sheets to be laminated, into the space between the blade 91 and the upper and lower jaws, and then rotates the operating lever 66 in clockwise direction about the fulcrum 68 so as to move the links 62 about their pivot pins 60 and 64 from the position shown in Fig. 2 to the position shown in Fig. 5, in which the bolt 78 is raised to an upper position by action of the lower hooked end of the latch 76 which engages the under side of the adjacent end of the bolt 78. The upward movement of the bolt 78 causes the link 94 to rotate the arm 92 in clockwise direction, thus rotating the rod 88 about the bearings 87. Rotation of the rod 88 causes the folding blade to enter between the upper and lower jaws a predetermined distance, thus folding the mouth of the bag upon itself, as shown in Fig. 5.

Continued upward movement of the latch 76 disengages the lower hooked end thereof from the end of the bolt 78 and the spring 118 now snaps the link 94, the arm 92, the arm 96, and the bolt 78 carried thereby down, or back to the posi-

tion shown in Fig. 2. This movement of the parts rotates the rod 88 in counterclockwise direction and thus withdraws the blade 91 from between the jaws.

Continued rotation of the operating lever 66 in clockwise direction further raises the pivot point 60 and the adjacent end of the rocker arm 48 and, by causing the links 42 to move from the inclined position of Fig. 2 toward the vertical position of Fig. 6, raises the end of the arm 32, thus depressing the upper jaw down upon the lower jaw, as shown in Fig. 6. In this position, the jaws apply heat and some pressure to the mouth of the bag.

Additional rotation of the operating lever in clockwise direction about the fulcrum 68 further rotates the rocker arm 48 in counterclockwise direction about the pivot pin 52 until it forms a very acute angle with a vertical plane passing through the axis of the pivot pin 52. The links 42 are now substantially vertical, thus further raising the end of the arm 32 and exerting additional downward force on the upper jaw so as to apply increased pressure. As illustrated in Fig. 7, the links 62 now slope downwardly from the pivot pin 60 in the direction of the jaws. In this position, the upper end of the spring 82 abuts the under side of the adjustable bolt 36, which is carried by the cross piece 34 connecting the arms 30. The bolt 36 and the spring 82 thus form a cushioned and adjustable stop for limiting or predetermining the extent to which the rocker arm 48 may be rotated in counterclockwise direction. Obviously, the lower the bottom end of the bolt 36 relative to the cross piece 34, the smaller the range of possible movement of the parts and vice versa.

When pressure on the foot lever is released, the parts return automatically to the position shown in Fig. 2, in which the lower hooked end of the latch 76 again engages the end of the bolt 78 and the apparatus is ready for another cycle of operation.

The extent to which the blade 91 enters between the jaws is regulated by varying the position of the bolt 78 relative to the latch 76. For example, if the bolt protrudes to a greater extent towards the latch, the hooked lower end of the latch will engage a larger portion of the under side of the bolt and the latch will have to be raised a greater distance before it will be disengaged from the end of the bolt. Since raising the end of the bolt raises the links 94 and causes the arm 92 and the blade 91 to rotate in clockwise direction, it follows that the longer the duration of the engagement of the hooked end of the latch with the end of the bolt, the greater the penetration of the blade 91 between the jaws, and vice versa.

The extent to which the bolt 78 protrudes towards the latch 76 is regulated by varying the position of the plate 106 to the plate 112. For example, if the bolt 113 is loosened and the plate 106 is rotated in counterclockwise direction about the pin 107, the plate 106 will be lowered relative to the plate 112, the pin 110 carried by the bolt 78 will engage the wider portion of the slot 108, and the spring 80 will be able to push the bolt further to the left. If the procedure is reversed and the plate 106 is raised relative to the plate 112, the pin 110 will engage the lower, narrower portion of the slot 108 and will move the bolt to the right against the action of the spring 80, so as to reduce the extent to which

5

the end of the bolt 78 is engaged by the lower hooked end of the latch 76.

It will be seen from the foregoing that by movement of the foot pedal, or by mechanical actuation of the apparatus by a prime mover, the blade 91 moves in between the jaws, folds the material being joined, and moves out from between the jaws simultaneously with the movement of the movable jaw towards the fixed jaws. Also, it is to be noted that the pressure is applied in two, albeit continuous stages. Thus, when the operating lever is moved downwardly only until the jaws meet, one degree of pressure is applied. If, on the other hand, the movement of the operating lever is continued until the links 62 assume the position of Fig. 7 and the spring 82 abuts the lower end of the adjustment bolt 36, another and greater degree of pressure is exerted.

The blade 91 does not only fold the material between the jaws so as to provide increased strength but, in so doing, the blade obviates the necessity of manually inserting the material between the jaws, thus preventing, or at least minimizing possible injury to the fingers of the operator.

In this connection, it is pointed out that the blade 91 can be used for only inserting the material between the jaws without folding it. For example, if the margin of the material is of a reduced width, the action of the blade will merely cause such margin to enter the space between the jaws and to lie flat upon the surface of the lower jaw or to assume a position parallel to said jaw.

What I claim is:

1. Apparatus of the character stated including a frame, a first jaw fixedly carried by said frame, a movable arm, a second jaw carried by one end of said arm in registration with said first jaw, a first rocker member carried by said frame, means pivotally connecting the other end of said arm to said first rocker member, an operating lever, means fulcruming said lever to said frame, means pivotally connecting said first rocker member to the end of said operating lever, said first rocker member and its pivotal connections to said arm and to said operating lever being such that rotation of the end of said operating lever about its fulcrum point actuates said arm in a direction to cause said second jaw to move towards said first jaw, a second rocker member, means supporting said second rocker member near said jaws, a blade carried by said second rocker member intermediate means for automatically operatively connecting said first rocker arm to said second rocker arm during movement of said first rocker arm through a predetermined

6

distance, and for automatically disengaging said second rocker arm from said first rocker arm after the movement of said first rocker arm through said predetermined distance whereby said second rocker arm is actuated by the initial movement of said first rocker arm to cause said blade to enter the space between said jaws, and means biasing said rocker arm in a direction to withdraw said blade from between said jaws upon disengagement of said second rocker arm from said first rocker arm whereby said blade is automatically withdrawn from between said jaws while said second jaw is moving towards but before it abuts said first jaw.

15 2. The structure recited in claim 1 in which
said intermediate means is adjustable so as to
vary the length of the distance through which
the first rocker arm will travel with said second
rocker arm operatively connected thereto, there-
20 by to vary the extent to which said blade enters
between said jaws.

3. The structure recited in claim 1 in which said intermediate means is in the nature of a latch carried by said first rocker arm and a bolt 25 pivotally carried by said frame and so disposed that its end is engaged by said latch during the initial movement of said first rocker arm, said bolt being movable about its pivot in a direction opposite to the direction of movement of said 30 first rocker arm, whereby after said first rocker arm has moved through a predetermined distance, said bolt is disengaged from said latch.

4. The structure recited in claim 3 in which said intermediate means is in the nature of a latch carried by said first rocker arm, a bolt pivotally carried by said frame and so disposed that its end is engaged by said latch in one position of said first rocker arm, said bolt being movable about its pivot in a direction opposite to the direction of movement of said first rocker arm, whereby after said first rocker arm has moved to a predetermined position, said bolt is disengaged from said latch, and means for varying the position of said bolt relative to said latch to vary the point in the movement of said rocker arm at which said bolt is disengaged from said latch.

JOSEPH MARZIANI.
